United States Patent Office

Des. 230,962
Patented Mar. 26, 1974

230,962

CART

Edgar W. Detjen, Kiel, Wis., assignor to Gilson
Bros. Co., Plymouth, Wis.

Filed Jan. 20, 1972, Ser. No. 219,596

Term of patent 14 years

Int. Cl. D12—08

U.S. Cl. D12—88

FIG. 1 is a perspective view of a cart showing my new design.

FIG. 2 is a perspective view thereof with the seat and engine omitted for ease of illustration.

FIG. 3 is a front elevational view of the cart shown in FIG. 2.

FIG. 4 is a rear elevational view of the cart shown in FIG. 2.

FIG. 5 is a side elevational view of the cart shown in FIG. 2.

FIG. 6 is a perspective view of a cart showing a modified embodiment of my new design.

I claim:

The ornamental design for a cart, as shown and described.
